ROY H. RUNDLE, OF BURLINGAME, CALIFORNIA.

LUMINESCENT TUBE.

Application filed May 31, 1927. Serial No. 195,324.

This invention relates to improvements in luminescent tubes and more particularly to electrodes for luminous tubes using neon gas and mixtures thereof and similar gaseous media adapted to be rendered luminescent by electrical discharges therethrough.

In the present instance this invention will be described in connection with its application to luminescent tubes for sign purposes.

10 In the use of neon and similar gases in long tubes, great difficulty is experienced in properly evacuating the tubes of all occluded gases that may adhere to the interior walls of the tube and the electrodes confined therewith, before the luminiferous gas is introduced into the tube. After the introduction of the desired gas, trouble is experienced from latent gases that may emanate from the electrodes as they become heated by the electric 20 discharges therebetween. Neon gas is highly sensitive to dilution, absorption and attenuation especially by gases that may be latent within the electrodes or given off by electrolysis, volatilization and distillation of the electrodes after long usage. Such gases and gaseous mixtures vitiate the purity of the confined neon gas or other desired medium.

25 The principle object of this invention is to lower the cost of and speed up production and improve the product more especially by providing an electrode that will withstand the constant discharge of high tension electric current therefrom without deterioration or serious changes in its molecular structure,

30 even at high temperatures; whereby the disadvantages above set forth may be eliminated in the practice of this art. A further object of the invention is to construct the electrode of such material that it will withstand high temperature and maintain its integrity. Other objects and advantages will appear as this description progresses.

In this specification and the annexed drawings, the invention is illustrated in the form considered to be the best, but I do not wish to be understood as confining it to this form because it may be embodied in other forms, and it is also to be understood that in and by the claims following the description it is desired to cover the invention in whatsoever form it may be embodied.

In the accompanying one sheet of drawings, Fig. 1 is a diagrammatic view of a luminescent tube in an electric circuit and 55 equipped with electrodes in accordance with this invention. Fig. 2 is a longitudinal sec-

tion of the electrode chamber of such tubes, showing in enlarged detail an electrode constructed and mounted therein in accordance with this invention. Fig. 3 is a plan view 60 of the discharge end of the electrode.

In detail the construction illustrated in the drawings comprises the conventional alternating current generator 1 suitably connected with the transformer 2, the high tension current from which is connected by the wires 3 and 4 with the electrodes within the electrode chambers 5 and 6 on opposite ends of the luminescent tube 7. This combination of elements, with modifications to suit 65 particular conditions, is in accordance with present practice. The novelty of this invention resides within the electrodes, including their size; the material of which they are composed and their general structure. 70

In the past electrodes have been constructed of various metals, copper being the preferred metal in connection with neon gas. Practice has proved that such electrodes must have a relatively large area in order to 75 carry the necessary high tension current at a relatively low temperature. In some previous instances the irreducible minimum of area of the electrode has been fixed at 1.5 square decimeters, about 15000 sq. m. m. per ampere, below which minimum the electrodes overheat and disintegrate, with deleterious effect upon the neon gas, as previously described.

By the use of the present invention I have 80 been able to reduce the area of the electrode to 13000 sq. m. m. and under favorable circumstances to much less per ampere of discharge. This I am able to accomplish by the novel construction and material of which 85 the electrode is composed, it being capable of withstanding temperatures up to incandescence, without deleterious effects upon the electrode and with beneficial results in purifying the tube prior to the introduction 90 of the neon gas, and in maintaining its purity while producing the desired luminescence 100 within the tube.

So far as I am aware, I am the first to utilize in a luminescent tube, tungsten steel 105 wire as now composed and drawn for use in connection with incandescent lamps; and to make use of an incandescent or nearly incandescent electrode within an evacuated tube, prior to the introduction of neon gas 110 or other luminiferous media therein to season and prepare it for practical commercial

purposes. Two very important advantages in the use of tungsten in this combination is, first, its long life in the presence of neon gas in a luminescent tube; and secondly, the 5 advantage of raising the temperature of the electrode practically to incandescence in the preliminary scavenging and seasoning or evacuation of the tube prior to the introduction of the neon. The high temperature 10 materially aiding in rarefying and dislodging the occluded gases in cleansing the interior of the tube during the evacuation process, oven heating and annealing being dispensed with.

15 The cleansing or evacuation of the tube may be accomplished by any of the well known processes for that purpose and is accomplished substantially as follows, see Fig. 1: A vacuum pump or other evacuating apparatus is attached to the by-pass 8 communicating with the interior of the tube 7. The neon gas receptacle is also connected to this by-pass through the valve 9. The evacuation 20 of the tube proceeds until a low vacuum is attained that will permit of the heating of the electrode at opposite ends of the tube without oxidation or combustion of the same yet leave sufficient atmosphere to hold in pumpable suspension any impurities 25 dislodged within the tube. This condition is manifested by a slightly blue visible vapor within the tube. During the final stages of the evacuation of the tube, the electrode may be raised to incandescence or nearly that temperature by the electric current passed 30 therethrough. This temperature not only drives off occluded gases from the electrodes and the interior of the tube but also opens up the texture and releases any latent gases 35 from the material of the electrodes, glass walls or any substances therein that may later produce gases or gaseous effects deleterious to the desired gaseous media. After 40 the proper cleansing and evacuation of the tube is perfected as measured in the usual manner, the exhausting means is shut off at the valve 8'. The gaseous medium is then permitted to flow through the valve 9 into the interior of the tube in the usual manner.

45 After the desired quantity of gas, such as neon, is introduced into the tube as disclosed by the usual test, the by-pass 8 is fused off, completely sealing the gas within the tube 7. A method of purifying the tubes by 50 "purging" and a very good statement of conditions, useful in the practice of the art, is contained in the preamble of the United States Letters Patent to Machlett, 1,618,767, dated February 22, 1927. It is deemed unnecessary 55 in the present disclosure to go into the purification or preliminary treatment of neon gas for use in luminescent tubes, for various purposes, since practically pure neon gas can be obtained in the open market.

60 The pair of electrodes required in the en-

ergizing of a luminescent tube may be alike in construction. For that reason, only one will be described. The electrode chambers, such as 5—6, comprise bulbous enlargements fused or welded to the ends of the tube 7 as 70 at the points 10—10. In the present instance the electrode is supported by a tubular base 12 welded at 13 to the walls of the chamber 5. The terminal wires 3 and 4 are welded at 14 to a short length 15 of dumet metal, the 75 expansion and contraction co-efficient of which is practically the same as that of the glass in which it is embedded. The tubular form of base is preferred because it prevents the short bending and breaking of the terminal wires 3—4 where they are embedded in the supporting bases 12.

The electrode comprises a length of tungsten wire as used in incandescent lamps as previously stated. This wire is coiled into 85 a helix as at 16 butt welded at 17 to the protruding end of the dumet metal 17', which then supports the helix in axial alignment with the bore of the tube 7. The top coil 18 of the helix is bent into a continuous 90 annulus and spirally joins the coil beneath, of the helix, this gives an unbroken discharge surface at the end of the electrode in proximity to the open end of the tube 7 where it joins the electrode chamber 5—6. 95 Points or asperities on the electrode at this point, without the interposition of the coil 18, are liable to produce lateral discharges that may puncture the tube walls.

It is the present practice in the neon sign 100 art to use glass tubing about seven-sixteenths of an inch internal diameter and of any length. For this the present preferred electrode 16 is composed of tungsten wire as described, which is about .017 of an inch 105 external diameter. Four and one-half inches of wire is used in forming the helix 16, the coils of which are preferably about one-quarter of an inch outside diameter, the helix being approximately one-half an inch 110 long. The end 18 should not be closer than one half of an inch from the adjacent entrance to the end of the tube 7. The electrode chambers 5—6 are preferably about one inch in diameter.

These various dimensions are given merely as an aid in the practice of this invention and are not to be construed as limiting the same since any one or all of them may be varied and their ratios, proportions and interrelations changed without departing from the spirit of this invention, with suitable modifications obvious to those skilled in this art, in meeting particular conditions. The means as described herein have proved in 120 commercial practice the various advantages 125 and effects set forth.

The use of the tungsten filament in the electrodes, permits the simultaneous cleansing and seasoning of the tubes resulting in 130

a great saving of time, and cost and an improved quality of luminescent tube since the preheating is more uniform and manipulation reduced to the minimum.

5 The new method of cleansing the tubes in accordance with this invention is substantially as follows:

When the electrode has been completely assembled it is connected to a manifold by means of pure gum rubber connection, the manifold being connected to a mercury vapor vacuum pump. A high tension current of approximately fifteen to twenty thousand volts is then passed through the electrodes 10 heating the metal elements of same to incandescence, thereby driving off all the occluded gases that may have been contained therein. This intense heat is applied for a sufficient length of time to make absolutely sure that 15 all the metal elements of the electrode have been thoroughly degased. The electrodes are then disconnected from the manifold and with a fine air gun a salt solution is sprayed onto the metal elements of same thereby 20 sealing up the pores of the metal and preventing vaporization. A sodium chloride solution for spraying is preferred, but the same results might be obtained by using any 25 one of several other salt solutions having similar characteristics.

The temperature of the electrode under normal operating conditions being approximately 400 degrees is low enough so that the salt spray placed on the metal elements of 30 the electrodes is not dissipated.

This method of degasing and spraying makes it unnecessary to further cleanse the

elements of the electrode after it has been placed on the finished product. All the cleaning that is then necessary is to cleanse 40 the walls of the glass itself which can be done at a much lower temperature at the electrode than would otherwise be necessary.

As herein referred to luminescent tubes are distinguished by the presence therein of 45 gaseous media adapted to become luminous at low temperatures by the passage of an electric current. Incandescent tubes and bulbs are distinguished by the presence therein of filaments rendered incandescent 50 by the passage of the electric current. So far as I am aware it is novel to use such filaments in luminescent tubes.

Having thus described this invention what I claim and desire to secure by Letters Pat- 55 ent is:

1. A luminescent tube having an electrode composed of tungsten filament in the form of a helix, the end of said helix being bent 60 into an annulus.

2. The method of cleansing and seasoning luminescent tubes consisting of sealing tungsten electrodes within said tube; rarefying the atmosphere within said tube and passing an electric discharge between said electrodes 65 and so heating the same and maintaining a temperature high enough and for a duration long enough to drive off the occluded gases therefrom; then coating said electrodes with a glazing material to seal the pores thereof. 70

In witness whereof I have hereunto affixed my signature.

ROY H. RUNDLE.
